UNITED STATES PATENT OFFICE

165,690

THREE-WHEELED VEHICLE

Max W. Kistler, Rochester, N. Y., assignor to
American Brake Shoe Company, Wilmington,
Del., a corporation of Delaware

Application July 13, 1951, Serial No. 15,863

Term of patent 14 years

(Cl. D90—8)

To all whom it may concern:

Be it known that I, Max W. Kistler, a citizen of the United States, residing at Rochester, in the county of Monroe and State of New York, have invented a new, original, and ornamental Design for a Three-Wheeled Vehicle, of which the following is a specification, reference being made to the accompanying drawing, forming a part hereof.

In the drawings:

Figure 1 is a front perspective view of a three-wheeled vehicle, showing my new design; and Fig. 2 is a rear perspective view thereof.

I claim:

The ornamental design for a three-wheeled vehicle, substantially as shown.

MAX W. KISTLER.
